UNITED STATES PATENT OFFICE.

JOHN W. LAMBERT, OF ANDERSON, INDIANA, ASSIGNOR TO THE BUCKEYE MANUFACTURING COMPANY, OF ANDERSON, INDIANA.

FRICTION-GEARING.

SPECIFICATION forming part of Letters Patent No. 761,384, dated May 31, 1904.

Application filed July 19, 1902. Serial No. 116,168. (No model.)

To all whom it may concern:

Be it known that I, JOHN W. LAMBERT, a citizen of the United States of America, residing at Anderson, in the county of Madison and State of Indiana, have invented certain new and useful Improvements in Friction-Gearing, of which the following is a full, clear, and exact specification.

Figure 1 is a side elevation of sufficient parts 10 of an automobile-gearing to show my invention, and Fig. 2 is a face view of the main or driving disk.

This invention relates to that class of gearing in which the power is transmitted from 15 the driving-shaft to a driven shaft at right angles thereto by means of a pair of friction-disks, the periphery of one disk having a frictional engagement with the face of the other disk and adapted to be moved across the same 20 to vary the speed of the driven shaft, as more fully hereinafter set forth. In adapting this form of power-transmitting mechanism to motor-vehicles it has been found essential in order to obtain the necessary friction to have 25 one at least of the friction-surfaces made elastic, and the difficulty has been to obtain a combination of materials that will be durable and at the same time will insure the transmission of the full power; and it is the object of 30 this invention to overcome these drawbacks, as more fully set forth hereinafter.

In the drawings; A designates the main or driving disk, which is attached to the drive-shaft in the usual way and has fastened to its 35 bearing-face an aluminium disk *a* coextensive in superficial area to the face of the driving-disk. This aluminium disk abuts solidly against the face of the drive-disk and is fastened thereto by a series of screws *a'*, passed 40 through the disk and preferably arranged around close to the edge thereof outside of the usual working area of the disk, so that they will not ordinarily come in contact with the periphery of the driven disk and unduly wear 45 or injure the same.

The driven disk B is carried, as usual, on a shaft C at right angles to the drive-shaft and having its periphery *b* bearing upon the face of the aluminium disk, said periphery con-

sisting of a suitable elastic fiber, such as paper 50 or wood.

In practice I have found that this combination of aluminium and fiber bearing-surfaces gives the maximum degrees of friction and durability, thereby especially adapting the gear- 55 ing for use on motor-vehicles of the heavier kind, where the friction-surfaces are at times subjected to great strains and must therefore have a frictional contact of a high degree of efficiency in order to avoid slipping. It will 60 be observed that the aluminium is advantageous also, because it will not tarnish or rust appreciably, but will always present a smooth clean surface to the fiber periphery, so that 65 wear will be reduced to a minimum.

Having described my invention, what I claim, and desire to secure by Letters Patent, is—

1. In a power-transmitting mechanism, the combination of a pair of shafts, a friction-disk carried by each shaft, one disk having a bearing part of aluminium and the other a fiber part bearing upon said aluminium bearing part.

2. In power-transmitting mechanism, the combination of a drive-shaft and a driven shaft, a friction-disk carried by each shaft, the face of one disk being provided with an aluminium bearing-plate detachably secured thereto and the attaching means being outside 80 of the usual working area of the bearing-plate against which the periphery of the other disk bears.

3. In a power-transmitting mechanism, the combination of a driving-shaft, a friction-disk 85 on said shaft bearing a face of aluminium, and a driven shaft carrying a friction-disk, a fiber periphery secured to said disk and adapted to bear on the aluminium face of the driving-disk.

4. In a power-transmitting mechanism, the combination with a driving-shaft, a friction-disk carried thereby, a bearing-plate of aluminium for said disk, means for detachably securing said aluminium plate to the face of 95 said driving-disk, a driven shaft, the means for attaching the aluminium plate to the driving-disk being outside of the usual working

area of the disk, a disk mounted thereon, a fiber periphery secured to said disk and adapted to bear on the aluminium face of said driving-disk.

5 5. In a friction-transmitting mechanism, a wheel having a frictional surface of aluminium.

6. In a frictional gearing, the combination with a friction-disk having a surface of aluminium, of a transmitting-disk having an

elastic frictional surface bearing upon said aluminium surface.

In testimony whereof I hereunto affix my signature, in the presence of two witnesses, this 14th day of July, 1902.

JOHN W. LAMBERT.
